United States Patent Office.

ALEXANDER WEMYSS, OF PHILADELPHIA, PENNSYLVANIA, ASSIGNOR TO DAVID STUART AND RICHARD PETERSON, OF SAME PLACE.

Design No. 3,565, dated June 29, 1869.

DESIGN FOR A STOVE-DOOR BRACKET.

The Schedule referred to in these Letters Patent and making part of the same.

To all whom it may concern:

Be it known that I, ALEXANDER WEMYSS, of Philadelphia, county of Philadelphia, State of Pennsylvania, have originated a new Design for the Body of a Bracket for Stove-Doors; and I do hereby declare that the accompanying drawing, and following explanation thereof, form a full, clear, and exact description of the said design.

In the drawing—

Figure 1 represents a front view of the bracket, and Figure 2, a transverse section of the same.

In order to fully explain the design, it will be advisable to refer to the frame of the door, which is shown by red lines in the drawing; *a a*, fig. 1, representing parts of the two oval figures composing the door, *b*, fig. 2, the door-frame, and *c*, the body of the stove.

The bracket *A* extends from the frame of the door, to the body, as shown in the drawing, so as to form a pleasing continuation of the door and door-frame.

This body of a bracket is susceptible of being ornamented with a variety of minor designs, outlines of one class of ornaments being shown by dotted lines in fig. 1.

I claim the design for the body of a bracket, substantially as described, and illustrated in and by the accompanying drawing.

In testimony whereof, I have signed my name to this specification, in the presence of two subscribing witnesses.

ALEX. WEMYSS.

Witnesses:

JOHN WHITE,
LOUIS BOSWELL.
